DENTAL BITE METHOD

Application filed May 19, 1927. Serial No. 192,628.

This invention relates to dentistry and has particular reference to an improved dental bite method employed in the construction of artificial dentures.

At present the two principal methods of obtaining dental bites which are in general use, are known as "biscuit bite" and the "base plate bite," the former consisting in using a large piece of wax warmed to a soft consistency and placed in the mouth, the patient then closing the jaws to a distance approximately that required for the artificial teeth. This method while capable of rapid accomplishment, is very inaccurate and largely guesswork in view of the fact that the wax model is easily distorted during its removal from the mouth. In the latter method (the base plate bite) considerably more accurate results are obtained than in the former method, but the said latter method entails considerably more time and a greater degree of skill, for the reason that after the impressions have been obtained, models are made of each jaw. The wax is attached to the models, trimmed to the approximately correct distance between the jaws, then placed in the patient's mouth at this stage, removed and trimmed until the wax holds the jaws the correct distance apart and until proper restoration of the facial contour is obtained. The two wax models are then secured together in the mouth by means of a hot spatula, wire staples, or marked and secured after their removal. It is obvious that these steps require a considerable length of time in addition to a high degree of skill and the necessity of making models of both jaws.

The present invention comprehends an improved dental bite method which accomplishes results equally as well if not better than the second method above referred to, namely, the "base plate bite," and this more expeditiously than said method and without entailing the high degree of skill and care required thereby, while insuring an even or uniform impression of both gums.

With the above recited and other objects in view, reference is had to the following description and accompanying drawings in which the method is set forth, while the ap-

pended claims define the actual scope of the invention.

In the drawings—

Figure 1 is a plan view of one of the wax bite forms employed;

Fig. 2 is a sectional view through a receptacle filled with a heated liquid and illustrating the wax bites in the liquid, which discloses an important step in the method;

Fig. 3 is a perspective view of one of the wax bite forms.

In carrying the invention into practice, the method consists in employing two or more arcuate or horseshoe-shaped pieces of wax or other equivalent material, known as "bite forms," the number employed depending upon the distance indicated and decided upon by previous alveolar absorption, length of the lips, and length of the teeth required. The method further consists in the step of trimming the outer surfaces of said forms to correspond to the size and curves of the patient's jaws; securing said pieces or forms together in superimposed relation by any known means, and placing the same in water or any equivalent liquid which is heated to approximately a temperature of 120° F., so that the same may float partially submerged. The forms thus connected are placed in the water or liquid with the piece or form which is to receive the impression of the upper jaw disposed toward the bottom and with the piece which is to receive the lower jaw impression disposed toward the top. The reason for this is that the lower jaw being much sharper as a rule than the upper jaw, should have the hard side of the wax to bite into, whereas the upper jaw which has the broader reach and from which it is hard to obtain the impression has the softer side or form to bite into. It follows that the lower portion and side edges of the wax bite forms will be subjected to the greater degree of heat when floated in the heated liquid and will be softer than the upper portion. The bite forms remain in the water for approximately two minutes, during which time the outer surface will become softened while the core or central portion will remain relatively harder and less affected by the heat, thereby enabling the operator to remove

the bite forms from the mouth without warping, and permitting the said forms to remain firm while the operator adapts the softened surfaces to the ridges; removes the same from the mouth if necessary for trimming off any excess or flash, and replaces in the mouth as often as desired.

In the drawings A designates one of the bite forms which is composed of wax or an equivalent material of substantially horseshoe or arcuate shaped configuration. As previously stated, after the selection of two or more bite forms, the same are trimmed on the outer surfaces to correspond approximately to the size and curves of the patient's jaws. The said forms designated at A¹ and A² in Fig. 2 are then secured together in any desired manner in superimposed relation and placed or floated in the water W of a receptacle R, with the bite form A¹ which is to be used for the lower jaw disposed uppermost and with the bite form A² which is to be used for the upper jaw disposed lowermost. The bite forms are permitted for a period of approximately two minutes to remain in the water or other liquid W which has been previously brought to a temperature of approximately 120° F. It is obvious that this specific arrangement of the bite forms in the water permits the upper jaw bite A² to become softer than the lower jaw bite A¹ which is disposed uppermost. It is also obvious that the outer surfaces of the bite forms will become softer than the inside or core, which due to the fact that the heat in the length of time specified will not have an opportunity to penetrate the central portion or core, will permit the operator to handle the same without distortion or warping while placing, removing and replacing the forms in the mouth.

What is claimed is:

1. A method of obtaining a dental bite including the step of floating a plurality of connected superimposed bite forms in a heated liquid, whereby the lower form will be heated to a greater degree than the upper form.

2. A method of obtaining a dental bite, including the step of floating partially submerged, a plurality of connected superimposed bite forms in a heated liquid until one form becomes softened to a greater degree than the other form, with the inside or core portion of each form remaining hard.

3. A method of obtaining a dental bite, including the steps of floating partially submerged, a plurality of connected superimposed bite forms in a heated liquid until the side edges and lower portions become softened to a greater degree than the upper portion with the inside or core portion remaining hard, and then employing the lowermost bite form for the upper jaw impression and

the uppermost bite form for the lower jaw impression.

4. A method of obtaining a dental bite, consisting in trimming the outer surface of a plurality of bite forms to correspond respectively to the size and curvature of the patient's upper and lower jaws, connecting said trimmed bite forms in superposed relation, floating partially submerged superimposed connected bite forms in a heated liquid with the lowermost jaw forms disposed upwardly, removing the bite forms from the liquid when the side edges and lowermost portion have become softened to a greater degree than the uppermost portion and with the core or interior remaining hard.

5. A method of obtaining a dental bite, consisting in trimming the outer surface of a plurality of bite forms to correspond respectively to the size and curvature of the patient's upper and lower jaws, connecting said trimmed bite forms in superposed relation, floating partially submerged superimposed connected bite forms in a heated liquid with the lowermost jaw forms disposed upwardly, removing the bite forms from the liquid when the side edges and lowermost portion have become softened to a greater degree than the uppermost portion and with the core or interior remaining hard, then inserting the bite forms in the mouth, adapting the softened surfaces to the ridges, and removing the same.
